CLAIM

The ornamental design for a garment neckline guard as shown and described.

DESCRIPTION

FIG. 1 illustrates a front environmental view for a garment neckline guard, shown in a folded configuration.

FIG. 2 illustrates a front view for the garment neckline guard of FIG. 1, shown in a folded configuration.

FIG. 3 illustrates a rear view for the garment neckline guard of FIG. 1, shown in a folded configuration.

FIG. 4 illustrates a perspective view for the garment neckline guard of FIG. 1, shown in a folded configuration.

FIG. 5 illustrates a right side view for the garment neckline guard of FIG. 1, shown in a folded configuration.

FIG. 6 illustrates a left side view for the garment neckline guard of FIG. 1, shown in a folded configuration.

FIG. 7 illustrates a top view for the garment neckline guard of FIG. 1, shown in a folded configuration.

FIG. 8 illustrates a bottom view for the garment neckline guard of FIG. 1, shown in a folded configuration; and,

FIG. 9 illustrates a front view for the garment neckline guard of FIG. 1, shown in an unfolded or expanded configuration. The long broken lines in FIG. 1 illustrate an environment of the article and form no part of the claimed design. The small broken lines on the garment neckline guard illustrate portions of the article that form no part of the claimed design.
